UNITED STATES PATENT OFFICE

OLIVER P. MEGAHAN, OF NEW CASTLE, PENNSYLVANIA

CONDENSER FOR MOTOR-VEHICLE RADIATORS

Application filed December 29, 1928. Serial No. 329,244.

The object of this invention is to provide an improved device for conserving the water and alcohol employed in the cooling system of a combustion engine, such as used in motor vehicles. Other objects will appear from the disclosure herein.

According to the invention, briefly stated, there is employed in connection with the radiator cap a condensing chamber of special construction in which a fan is turned by an externally mounted wind wheel, said fan tending to draw cooling air into said chamber and agitate the mixture of air and vapors to condense the vapors rising from the radiator so that they may return to the body of the cooling liquid.

The invention is embodied in the example herein shown and described, the features of novelty being finally claimed.

20 In the accompanying drawing—

Figure 1 is a view in side elevation of the invention.

Fig. 2 is a vertical section of the same on a radiator with some parts in full.

25 Fig. 3 is a horizontal section of the device as on the line III—III Fig. 2 looking down.

In the views 5 designates the body of the radiator cap which is internally threaded to screw onto the water-supply-neck of the radiator as usual and as indicated in Fig. 2.

Connected with the top wall of the cap are two upwardly extending tubes 6, 6, on the upper ends of which is a chamber 7 made of two parts threaded together so that they can be separated at will. Around the ring near the top of the chamber 7 is a series of holes 7^a. Connected with the bottom of the chamber 7 between the tubes 6, 6, is a cup or chamber 8 forming a downward extension of the chamber 7. Said chamber is shown as connected with a tube 6 by perforations at 8^a.

The cup or chamber 8 is spaced from the cap and to that extent increases the cooling surfaces of the structure. Extending centrally upward from below the cap is a small tube 9 having in its upper end a bearing 10 in which is stepped the conical point of a shaft

45 11. The upper end of the tube 9 is provided with a number of perforations 9^a. Fixed on said shaft 11 within the chamber 7 is a fan

12, and fixed on the external portion of said shaft above the chamber is a wind wheel 4 adapted to be turned by the wind, either that naturally created or that artificially caused by the movement of the vehicle as when driven.

55 The lower end of the tube 9 is bulged as shown at 9^a to receive a funnel 13 of soft rubber or other suitable material said funnel fitting on the upper end of the usual overflow pipe 14 just below the water supply opening of the radiator.

60 The operation can be described as follows: The vapors from the radiator instead of escaping through the overflow pipe as usual 65 rise through the large tubes 6, 6, and are agitated, mixed, cooled and condensed by the cool air drawn through perforations 7^a into chamber 7 by the operation of the fan 12.

65 The condensate flows back to the body of the engine cooling liquid through said pipes 6, 6, and so also does the condensate collecting in the cup chamber 8 through hole 8^a.

70 The provision of the small tube 9 and its closed connection with the overflow pipe causes the vapors to rise from the radiator into the condensing structure but permits only a comparatively small drift of vapor from the condensing chamber through the overflow pipe. The holes in the small pipe 9 75 relieve excess pressure in the condensing apparatus.

75 It will be observed that with this construction a large part of the water or water and alcohol that evaporates as an incident of the 80 operation of the motor is returned to the radiator thereby lessening the burden of supplying liquids to the radiator and lessening the necessity for constant caution in the respect. Alcohol is not only quite expensive but 85 much more volatile than water hence a large saving is effected in cold weather by the use of the invention.

90 The forms of the parts can be changed without departing from the gist of the invention as claimed.

95 What I claim is:

100 1. A condenser for a motor vehicle radiator system comprising a cap, a chambered extension of said cap, said extension provided

with cool air vents, a fan in said chamber, and an exposed wind wheel operating said fan.

2. A condenser for a motor vehicle radiator system comprising a cap, a chambered extension of said cap, said extension provided with cool air vents, a fan in said chamber, an exposed wind wheel operating said fan, and a central tube in the cap opening into said chamber and means for communicatingly connecting said tube with the overflow pipe of the radiator when the cap is applied.

3. A condenser for a motor vehicle radiator system comprising a cap, a chambered extension of said cap including an upper portion connected by tubes with the cap, a downward central extension therefrom, one of said tubes extending downwardly below the cap, means connecting said tube with the overflow pipe of the radiator, a fan in the chamber of said extension and an exposed wind wheel to operate said fan.

4. A condenser for a motor vehicle radiator system comprising a radiator cap provided with a chamber having air vents, a fan in said chamber to agitate the vapors coming through the cap and a wind wheel connected with the fan for operating the latter.

5. A condenser for a motor vehicle radiator system comprising a radiator cap provided with a chamber having air vents, a fan in said chamber to agitate the vapors coming through the cap, and means for driving the fan.

OLIVER P. MEGAHAN.
